DESIGN FOR A JUG

Carl H. Steinbiss, San Francisco, Calif., assignor to Lyons-Magnus, Inc., San Francisco, Calif., a corporation of Delaware

Application April 29, 1936, Serial No. 62,376

Term of patent 14 years

To all whom it may concern:

Be it known that I, Carl H. Steinbiss, a citizen of the United States, residing at San Francisco, in the county of San Francisco and State of California, have invented a new, original, and ornamental Design for a Jug, of which the following is a specification, reference being had to the accompanying drawing, forming a part thereof.

I claim:

The ornamental design for a jug substantially as shown.

CARL H. STEINBISS.
